UNITED STATES PATENT OFFICE.

MAUDE SIEGEL, OF NEW YORK, N. Y., ASSIGNOR TO FRANKLIN SIMON & CO. INC., OF NEW YORK, N. Y., A CORPORATION OF NEW YORK.

DESIGN FOR A DRESS.

Application filed January 13, 1927. Serial No. 20,363. Term of patent $3\frac{1}{2}$ years.

To all whom it may concern:

Be it known that I, MAUDE SIEGEL, a citizen of the United States, and a resident of the city of New York borough of Manhattan, in the county and State of New York, have invented a new, original, and ornamental Design for Dress, of which the following is a specification, reference being had to the accompanying drawing, forming part thereof, wherein—

The dress is distinguished by a tunic effect formed with aligned yoke members together with tabs and aligned sections on the sleeves carrying out the same ornamental effect as the tunic. The dress is also distinguished by the use of a belt with a buckle near one side and a similar belt structure around each wrist.

Figure 1 is a front view of a dress, showing my new design, the dress being illustrated on a figure.

Figure 2 is an enlarged fragmentary view showing the front of the lower part of the sleeves illustrated in Figure 1, this view illustrating the tongue or tab and belt arrangement.

Figure 3 is a view similar to Figure 2 but showing the opposite side of the sleeve and the arrangement of belt at that point.

I claim:

The ornamental design for a dress, substantially as shown and described.

MAUDE SIEGEL.
